UNITED STATES PATENT OFFICE.

LOUIS V. ARONSON, OF NEWARK, NEW JERSEY.

DESIGN FOR A CLOCK HOLDER OR SUPPORT.

No, 39,330.

Specification for Design.

Patented June 2, 1908.

Application filed March 14, 1908. Serial No. 421,273. Term of patent 7 years.

To all whom it may concern:

Be it known that I, LOUIS V. ARONSON, a citizen of the United States, residing in the city of Newark, in the county of Essex and State of New Jersey, have invented a new, original, and ornamental Design for a Clock Holder or Support, of which the following is a description.

Figure 1 is a front view of my new design, and Fig. 2 is a side view of the same.

I claim:
The ornamental design for a clock holder or support, as shown.

LOUIS V. ARONSON.

Witnesses:

L. FIRNER,
C. A. ALLISTON.
